(57) **CLAIM**

The ornamental design for a stirring body, as shown and described.

DESCRIPTION

FIG. 1 is an isometric view of a stirring body, nonessential elements being shown in dotted lines.

FIG. 2 is an elevational view of the stirring body of FIG. 1, the rear and the right and left side elevational views being the same as shown in FIG. 2, and nonessential elements being shown in dotted lines.

FIG. 3 is a plan view of the stirring body of FIGS. 1 and 2, nonessential elements being shown in dotted lines.

FIG. 4 is an isometric view of a second embodiment of a stirring body, nonessential elements being shown in dotted lines.

FIG. 5 is an elevational view of the stirring body of FIG. 4, the rear and the right and left side elevational views being the same as shown in FIG. 5, and nonessential elements being shown in dotted lines.

FIG. 6 is a plan view of the stirring body of FIGS. 4 and 5, nonessential elements being shown in dotted lines.

FIG. 7 is an isometric view of a third embodiment of a stirring body.

FIG. 8 is an elevational view of the stirring body of FIG. 7, the rear and the right and left side elevational views being the same as shown in FIG. 8.

FIG. 9 is a plan view of the stirring body of FIGS. 7 and 8.

FIG. 10 is an isometric view of a fourth embodiment of a stirring body.

FIG. 11 is an elevational view of the stirring body of FIG. 10, the rear and the right and left side elevational views being the same as shown in FIG. 11; and,

FIG. 12 is a plan view of the stirring body of FIGS. 10 and 11. The broken line showing in FIGS. 1-6 is included for the purpose of illustrating and forms no part of the claimed design.
